UNITED STATES PATENT OFFICE.

JOHN A. BERGREN, OF LAKE PARK, MINNESOTA, ASSIGNEE OF ONE-HALF TO HERMAN S. WILSON, OF LAKE PARK, MINNESOTA.

GRAIN-TANK.

1,207,842.

Specification of Letters Patent. Patented Dec. 12, 1916.

Application filed May 9, 1914. Serial No. 837,561.

To all whom it may concern:

Be it known that I, JOHN A. BERGREN, a citizen of the United States, residing at Lake Park, in the county of Becker and State of Minnesota, have invented certain new and useful Improvements in Grain-Tanks, of which the following is a specification.

The object of my invention is to provide a tank so constructed that it may be fitted to rest and be held on the bolsters of a wagon to take the place of the box, and one which when fitted to place is very rigid forming substantially a part of the wagon.

A further object is to so connect the parts of the tank that the tank may be knocked down or the parts may be separated to facilitate handling in shipping and in placing the tank on the wagon, and further to so construct the structure that parts may be removed and a standard form and size of wagon box will yet be retained.

With other objects in view, which will be referred to, my invention consists in the peculiar combination and novel arrangement of the parts, such as will be hereinafter more fully described in connection with the accompanying drawings and more particularly pointed out in the appended claims.

In the drawings:—Figure 1 is a view in side elevation of one adaptation of my improved tank. Fig. 2 is a transverse vertical sectional view through the tank looking toward the rear end. Fig. 3 is a view in top plan of the rear end of the tank. Fig. 4 is a detail perspective view to show the means for holding the end gate in place. Fig. 5 is an enlarged perspective view of one of the angle braces used to give strength to the structure of the tank. Fig. 6 is a transverse vertical sectional view through one side of the tank showing the members comprising this side in their detached position. Fig. 7 is a fragmentary detail sectional view to show the interlocking connection between the members of the side. Fig. 8 is a view similar to Fig. 2 to show a slightly modified form which my invention might take.

The tank comprises a bottom member or floor 1 preferably composed of a single sheet of metal, and this body member has cross members 2 in the present instance disclosed as channel iron secured thereto at several points along its length to give additional

strength. While I have shown and shall describe the bottom member 1 and the other members comprising the tank as composed of sheet metal, it will be understood that these parts might as readily be built up of wood properly reinforced by cross braces. 60 The bottom member 1 is stopped at its edges a short distance from the end of the cross braces 2 and these edges are bent to form flanges 3 and 4.

The side members 5 and 6 reinforced by 65 transversely extending channel pieces 7 and 8 have flanges 9 and 10, respectively formed on their lower edges and these flanges are so constructed that they fit within and engage the flanges 3 and 4 of the bottom member 1 70 to form a tight joint. The side members 5 and 6 have rolled flanges formed on their upper edges as better shown in Fig. 7. Extension side members 11 and 12 are constructed to fit and be secured above the side 75 members 5 and 6 and are flared as better shown in Fig. 2 to give greater capacity to the tank. These extension sides 11 and 12 have grooved flanges 13 and 14 provided on their lower edges to engage with and fit over 80 the rolled flanges 15 and 16 of the side members 5 and 6, respectively, and this interlocking connection between the side members and the extension side members together with the interlocking connection between the 85 side members and the bottom member form a structure the side walls and bottom or floor of which are substantially one piece. The extension side members 11 and 12 have channel irons 17 and 18 secured thereon to 90 be in alignment with the channel pieces 7 and 8 of the side members 5 and 6 and these aligned channel pieces are disposed along the side members to be in vertical alinement with the cross braces 2 of the bottom member 1. 95

An end gate 19 is received between the side members 5 and 6 at the tail end of the tank to rest against the upper face of the floor member 1; an extension end gate 20 having 100 its end shaped to conform to the inner contour of the extension side members 11 and 12 is mounted to rest at its lower edge upon the upper edge of the end gate 19 between these extension side members, and a like end gate 105 and extension end gate are provided at the forward end of the tank. To insure that this end gate and extension end gate are at

all times held against lateral or side movement, the angle irons 21 are secured to the side members and extension side members to have their flat faces disposed toward the end 5 of these members, and a second angle iron 22 is mounted adjacent the flat face of each of the angle irons 21 to extend parallel therewith and to have sliding connection on the pins 23 which pass through slots 24 formed 10 through the angle iron 22. Brackets 25 are mounted on each of the members adjacent the angle iron 22 and clamping bolts 26 are threaded through these brackets 25 to engage with the flange of the angle iron and 15 clamp this angle iron against the end gate and the extension end gate which is held on its opposite side by one of the angle irons 21.

An opening 27 is formed through the end gate 19; guides 28 are secured transversely 20 of the end gate 19 adjacent the edges of the opening 27 and these guides are made continuous to the top of the end gate 20 by guides 29 secured thereto in vertical alignment with the guides 28. A slide 30 is 25 mounted to move in the guides 28 and 29 to a position to close over the opening 27 and a handle 31 is secured at its lower end to the plate 30 and is passed up through guides 32 to a point where it is accessible to be manually raised or lowered to move the plate 30. A hand set screw 33 is provided through one 30 of the brackets 32 to be screwed in against the handle 31 to hold the plate 30 in its adjusted position.

The channel pieces 7 and 8 secured to the 35 side members 5 and 6 have notches 34 and 35 formed through the sides thereof; angle brackets 36 and 37 are pivoted between the sides of the angle pieces 17 and 18 of the extension side members 11 and 12 and on their lower end are provided with pins 38 and 39 to be received in the notches 34 and 35, respectively. These angle brackets, the structure of which is better disclosed in Fig. 5, 40 are of a shape to fit the flare of the extension side members 11 and 12 and when fitted to place hold these extension side members against too great inward movement. Bearings 40 are secured to each end of the channel members 2 and the adjustable side braces 41 pivotally connected at their upper ends at 42 with the channel members 17 and 18 of the extension side members 11 and 12 have a 45 detachable pivotal connection with these bearings 40. The braces 41 are made adjustable by turnbuckles 43 working on right and left hand threads on the two members of this brace and the bearings 44 are provided on the angle brackets 36 and 37 to receive these braces 41 and hold them against buckling.

A channel iron 45 is riveted or otherwise 50 secured to the bottom member 1 to receive the front bolster of the wagon and channel irons 46 are secured in a vertical position on

the side members 5 and 6 to receive the stakes of the bolsters. This channel iron 45 is secured at such a position that the rear bolster comes within one of the cross-brace channel irons 2 of the bottom member and clamp bolts 47 may be provided through one side of this channel iron to be screwed up against the bolster to hold the tank in place. In some instances it may be found desirable 70 to connect the truss rods 48 between two of the cross members 2 of the bottom member 1 and to provide these truss members with turnbuckles 49 so that they can be tightened 75 to prevent sagging of the bottom member under excessive load.

In use, the parts are assembled as shown 80 in Figs. 1, 2 and 3, and are held rigidly in their assembled position by the tightening of the adjustable braces 41 thus making a complete tank, but, when it is desired to 85 remove the extension sides and the extension end gate to provide merely a box for the wagon, this is accomplished by releasing these adjustable braces 41 from the bearings 40 on the cross channel irons 2 of the 90 body member, which permit the parts to be swung to the position disclosed in Fig. 6. When the adjustable braces are released the pins 38 and 39 may be very readily removed 95 from the notches 34 and 35 and the adjustable side members can be entirely separated from the side members 5 and 6 which comprise the body of the box of the wagon, also the extension end gate can be removed.

In the disclosure in Fig. 8, the lower part 100 of the tank is varied slightly from the structure hereinbefore described. In this disclosure the side members 5' and 6' are made as a continuation of the bottom or floor 1' of the tank and their point of connection is 105 made a gradual curve. In this adaptation the channel members 7' and 8' secured to the side members 5' and 6' would be at their lower ends connected with the cross members 2' secured to the bottom 1', otherwise the 110 structure is identical with the disclosure of the preferred form and like reference characters have been applied.

From the foregoing it will be seen that I 115 have provided a grain tank constructed to be fitted on a wagon, comprising few parts simple in manufacture and assemblage and which may be handled in knock-down form and when assembled present a structure as rigid and substantial as though the parts 120 were permanently connected together, further it will be seen that by the removal of certain parts of the structure of the grain tank a wagon box of standard form and size is provided.

While I have herein shown and described 125 only specific forms of my invention, it will be understood that slight changes might be made in the form and arrangement of the several parts without departing from the 130

spirit and scope of my invention, and hence I do not wish to be limited thereto except for such limitations as the claims may import.

5. I claim:—

1. A grain tank comprising a bottom member, side members mounted on said bottom member to be detachable therefrom, extension side members loosely and detachably mounted on said side members, and detachable means connected between the extension side members and the bottom member to have connection with the side members and to thus hold the side members and extension side members rigidly connected with said bottom while at the same time allowing removal of the side and extension side members when the connecting means is detached.

2. A grain tank comprising a bottom provided at its sides with portions of an interfitting connecting seam, side members provided with mating portions of the interlocking seam on their lower edges to be fitted in conjunction with the bottom portion and at their upper edges having portions of a second connecting seam, extension side members provided on their lower edges with mating portions of interlocking connecting seams to be fitted with the second mentioned seams of the side members, end gates mounted in interfitting relation between the side members and extension side members, and clamping rods connected between the bottom member and the extension sides to have connection with the side members and to thus secure the side members and said extension side members rigidly in place and to hold the end gates in the proper relation, while at the same time being readily detachable to allow removal of the side and extension side members.

3. A grain tank comprising a sheet metal bottom member provided with upturned flanges at the edges thereof, side members provided with flanges to be received in interlocking relation with the flanges of the bottom member to be detachably mounted thereon, extension side members mounted on the sides of the body as hereinbefore set forth, and means connected between the body portion and the extension side members to hold said extension side members and the sides rigidly connected with the bottom member.

5. A grain tank comprising a bottom provided with one member of an interlocking connection formed along each side edge thereof, side members provided with the fitting member of the interlocking connection to be mounted upon said body and to be detachable therefrom, extension side members adapted to rest on the upper edges of said side members, brackets to engage between the side of the body and said extension side members, and means connected between said

extension sides and the body to engage with said bracket to hold said extension sides and the side members rigidly connected in place.

5. A grain tank comprising a bottom provided at its side edges with one member of an interlocking connection, side members provided with the interfitting member of the interlocking connection to be connected along the sides of said body in an interlocking and detachable relation, extension side members mounted on the sides of said body portion, brackets engaged between said extension side members and the sides of said body, and adjustable side braces connected between the body portion and said extension sides to coöperate with said brackets to hold the extension side members rigidly connected upon the sides of the tank.

6. A grain tank consisting of a body portion comprising a bottom and sides, extension side members mounted on the sides of said body and flared outwardly therefrom, angle brackets adapted to engage between the sides of the body and said extension side members within the angle formed by the flaring of said members, and braces connected between said extension side members and the bottom to have bearing against the brackets to hold the extension side members rigidly connected in place.

7. A grain tank comprising a bottom member, side members mounted on said bottom member to have interlocking connection therewith and to be detachable, extension side members mounted on said side members and flared therefrom to make the tank of greater transverse dimension, angle brackets connected between said side members and extension side members in the angles formed by the flaring of the extension sides and provided with bearings on the outer faces thereof, and adjustable braces secured between the bottom member and said extension side members to rest within the bearings of said angle brackets to hold all of the parts rigidly connected together.

8. A grain tank comprising a bottom member, side members mounted to have interlocking connection with said bottom member and to be detachable therefrom, extension side members mounted on said side members and flared therefrom to make the tank in the upper part of greater transverse dimension, angle brackets connected between said side members and extension side members to rest within the angle formed by the flare of the extension side members, and adjustable means connected between the extension side members and the bottom member to engage with the brackets and hold all of the parts rigidly connected together.

9. A grain tank comprising a bottom member, side members mounted to have interlocking connection with said bottom member and to be detachable therefrom, exten-

4

sion side members mounted on said side members and flared therefrom to make the tank in its upper portion of greater transverse dimension, angle brackets connected 5 between said side members and extension side members to rest in the angle formed by the flare of the latter, end gates mounted between said side members and said extension side members to form the ends of the tank, 10 and extensible means connected between the extension side members and the bottom member to engage and coöperate with said brackets to hold the structure rigidly connected together.

15 10. A grain tank adapted for use on a wagon consisting of a body portion comprising bottom and sides, extension side mem-

bers mounted on said sides and flared therefrom to form an angle between said sides and the extension side members, brackets 20 connected between said extension side members and said sides to rest in the angle formed therebetween, and adjustable side braces connected between said extension sides and the body to have bearing engagement with said brackets to hold the extension sides rigidly connected with the body and to permit detachment therefrom.

In testimony whereof I affix my signature in presence of two witnesses.

JOHN A. BERGREN.
